UNITED STATES PATENT OFFICE

JOHN ORMOND KER, OF OTTAWA, ONTARIO, CANADA, ASSIGNOR TO HARRY KETCHUM,
OF LUZERNE, NEW YORK

ANIMAL MARKING TOOL

Application filed May 3, 1929. Serial No. 360,189.

This invention relates to improvements in animal marking tools generally and more particularly to that class of marking tool for tattooing and branding live stock.

5 The objects of the invention are to provide a light durable and handy tool of this character for marking animals such as cattle, sheep, hogs, horses, birds and the like by tattooing an identification mark thereon.

10 An essential objects of the invention is to provide a tool of this class with interchangeable tattoo carrying blocks so constructed that blocks can be quickly changed and readily secured therein for use, and whereby friction and consequent wear and tear without clogging of the blocks is completely avoided. In other words, my improved tool is particularly adapted for speed and efficiency in the marking of live stock.

15 I am aware that animal marking tools or instruments carrying tattoo type blocks are at present in use, the blocks being slidably fitted longitudinally or transversely and being retained by a clamping screw, or the like or are arranged in holes and held by a cotter pin. Both being manually operated to release or retain the blocks entailing loss of time and, as above mentioned, wear and tear. With my improved tool, the clamping or retaining 20 screw or cotter pin are eliminated, and the blocks collectively and selectively retained rigid or released.

25 The novel features of the invention comprise a character holder adapted to carry type or tattoo blocks and formed with a continuous slot adapted to house a locking plate or member swingingly mounted therein slots in the blocks or registering with said continuous slot, whereby on said member being swung outwardly, the blocks are disengaged and released, means associated with the slot and locking member for automatically locking the latter when swung inwardly.

30 Referring now to the drawings in which, like numerals of reference, indicate corre-

sponding parts in each figure, and in which:—

Fig. 1 is an enlarged perspective view of the tool or instrument as a whole in the form adapted for brand-tattooing animals on the body.

50 Fig. 2 is an underside view of the character holder with type carrying blocks.

Fig. 3 is a similar view with the blocks removed.

55 Fig. 4 is a longitudinal section of the character holder, with the blocks removed and showing the locking member for the blocks.

Fig. 5 is a section on line 5—5 of Fig. 2.

Fig. 6 is a section on line 6—6 of Fig. 4.

60 Fig. 7 is a perspective view of a block with slotted stem for engagement with locking member.

65 Fig. 8 is an enlarged perspective view of a slightly modified form of the instrument or tool for tattooing the ear of an animal and marking birds.

70 Referring now more particularly to the drawings in which an example of my invention is disclosed, A indicates the tool as a whole (Fig. 1) for placing an identification mark on the body and particularly the hip of live stock, and comprising a bar 10 provided with a handle 11 at its outer end and bent adjacent the opposite end to form a flat portion

75 12 to which is secured in any well known manner and preferably integral therewith, a character holder 13 consisting of a metal block formed with a series of spaced circular openings 14, adapted to engage with the stems 15,

see Fig. 7 of type blocks 16. The underside 80 of these blocks being former with bosses 17 for engagement with recesses 18 in the face 19

of the holder 13, whereby the correct position of the blocks 16 in the holder 13 is maintained. The blocks 16 are provided, as here 85

shown, on their front faces with tattoo needles 20 of known construction and hereinafter more fully referred to.

90 Coming now to the essential and novel features of the invention, the holder 13 is formed

with a continuous slot 21, in the side therein, open at one end and closed at the other end in which is housed a locking member or plate 22, pivotally mounted as at 23, and protruding slightly at the open end as at 24, beyond the holder, whereby it is conveniently operable from without to be swung inwardly into block retaining position or outwardly to release the blocks.

10 Co-operating with the slot 21 in the holder 13 and adapted to register therewith, are slots 25 formed in the stems 15 of the blocks 16, so that when the locking member or plate 22 is swung inwardly, as shown in Figs. 1 and 8 to engage with the slot 21, it will also engage the slots 25 to rigidly retain the blocks within the holder, ready for action. Simultaneously with this operation the plate 22 is automatically locked by means of a pin 26 sunk, as at 27, in the holder and spring pressed, by means of a spring plate 28 on the top of the holder and engaging with the bottom of the pin. The plate 28 is retained in position by a screw 29 and causes the pin 26 to protrude slightly within the slot 21 and to automatically engage with a recess 30 in the underside of the locking member when the latter is moved inwardly to lock same in engagement with the type blocks.

30 In Fig. 8 a form of tool is shown for tattooing the ear of an animal or marking poultry and birds comprising handle members 31 and 32 pivoted as at 33 and provided with coil spring 34. These members are formed with jaws 35 and 36 respectively, the jaw 35 terminating in a character holder 37 as previously fully described, while the jaw 36 terminates in a plate portion 38 registering with the holder 37.

40 From the foregoing, the operation of my improved tool or instrument for marking live stock and birds will be readily understood. In the form, as disclosed in Fig. 1, the number, name or mark to be transferred to the hip or body of an animal, is formed by selecting the type or tattoo blocks carrying the characters that make up the mark. These blocks, after the locking plate 22 has been swung outwardly, are then inserted in the openings 14 of the holder 13 or 37, care being taken that the bosses 17 engage with the recesses 18 associated with the openings 14 and whereby the correct position, as to printing and fitting of the blocks 15, within the holder is accurately accomplished.

50 The slots 25 in the blocks will now be in alignment with one another and register with the slot 21 in the holder within which is swingingly mounted the locking member 22, which is then swung inwardly to engage with the slot 21 and with the slots 25 in the individual blocks thereby securely retaining them in position. At the same time the pin 26 engages with the member 22 to lock it. To quickly and efficiently release or change the

blocks, it is only necessary to press the protruding end 24 of the locking member when it will be released and drop out immediately leaving the holder ready for a fresh supply. Furthermore, the locking member 22 can be 70 operated to release only one or more of the blocks while retaining the remainder. In other words, the blocks may be selectively or collectively released by the locking plate. Further means for indicating that the blocks 75 are correctly arranged in the holder, are the guide lugs 39 on one side thereof, which must be an alignment on one side to ensure this result.

The modified form as disclosed in Fig. 8 80 is placed on the inside of the animal's ear and compressed, and in the case of poultry and birds on a portion of the skin.

Tattoo ink is thoroughly smeared over the puncture made by the needles to provide a 85 clear distinct mark. As the punctures heal, the skin grows over the tattoo ink leaving the mark permanent inside the animal's ear or on the body thereof.

90 While a specific embodiment of this invention is herein shown and described, it should be clearly understood that the detailed parts in the preferred forms, and also that the preferred forms may be varied from time to time, depending upon the circumstances and 95 conditions governing, and governed by, the development of this invention and the arts to which it is incident, so the interested inquirer is directed to interpret the scope of this invention from the claims, in which its 100 spirit is broadly generalized.

I claim:

1. A tattoo marker for animals and the like comprising a pair of pivotally connected jaw members with spring actuated handles, 105 the ends of the jaws being formed with plate portions registering with one another, one of said portions being provided with a series of spaced holes, needle carrying blocks formed with slotted stems for detachable engagement with said portion, a continuous slot in said portion communicating with and common to said blocks, a locking member or bar swingingly mounted in said slot and protruding longitudinally therefrom with handling means and adapted when swung inwardly to engage with the blocks to retain them in position and when swung outwardly to release said blocks, means for automatically locking the bar in operative engagement with the blocks and manually operable means for unlocking said bar, means in the plate portion for aligning the blocks.

115 2. In a tattoo marker for animals and the like of the character described, the combination with a pair of pivotally connected jaw members formed with T-shaped ends and having in one of said ends a series of openings and common to said openings a longitudinal- 120 ly extending slot, a locking bar pivotally 125

mounted in said slot and protruding at one end, needle carrying blocks formed with stems for detachable engagement with said plate and provided with slots registering with the slot in the plate for engagement with the locking bar and means associated with the plate for automatically locking said bar and means associated with the bar and the plate for manually unlocking said bar.

10 In witness whereof I have hereunto set my hand.

JOHN ORMOND KER.
